CLAIM

The ornamental design for an imaging device with housing, as shown and described.

DESCRIPTION

FIG. 1 is a front, top, left isometric view of an ornamental design for an imaging device with housing;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof; and,

FIG. 8 is a rear, bottom, right isometric view thereof.

The ornamental design that is claimed is shown in solid lines in the drawings. The broken lines in the drawings show portions of an imaging device with housing that form no part of the claimed design. The dash-dot broken lines in the drawings are included to define boundaries of the claim only and form no part of the claimed design.
